ARTICLE SUPPORTING BRACKET

Ronald E. Ross, Long Island City, N. Y.

Application June 5, 1948, Serial No. 31,377

5 Claims. (Cl. 211—123)

1

This invention relates to devices for supporting various types and kinds of articles, such as belts, neckties and the like, to retain the same against accidental displacement. More particularly, the invention deals with a device comprising a frame having a pivoted link normally constituting part of the frame and movable into an open position to facilitate attachment and detachment of the article or an article supporting member with respect thereto.

The novel features of the invention will be best understood from the following descriptions when taken together with the accompanying drawing, in which certain embodiments of the invention are disclosed, and in which the separate parts are designated by suitable reference characters in each of the views; and in which:

Fig. 1 is a perspective view of a bracket made according to my invention, indicating the manner of its use.

Fig. 2 is an enlarged exploded perspective view of parts of the bracket detached, preparatory to assemblage.

Fig. 3 is a section on the line 3—3 of Fig. 1, on an enlarged scale.

Fig. 4 is a plan view of a modified form of construction which I employ; and

Fig. 5 is a partial section on the line 5—5 of Fig. 4.

In Fig. 1 of the drawing, I have shown a bracket comprising a large elliptical loop member 10 on the back rod 11 of which is secured at widely spaced intervals, two attaching plate portions 12 and 12' for mounting the bracket in connection with a suitable support.

The front of the loop 10 is formed by independent and spaced members 13 and 14 joined by a bridging link 15. The members 13 and 14 preferably have on their upper surfaces, grooves, as at 16, for positioning articles, such as the buckles 17 of belts 18 thereon. The free end of the part 13 of the bracket has a recess 19 in the front face thereof and the remaining tongue member 20 has a socket 21 opening to the inner surface to receive part of a coil spring 22. This surface is also recessed, as at 23, to receive one end 24 of the spring. The link 15 has its pivot end recessed, as seen at 25, to receive the tongue 26, the end portion forming a tongue 26 on the link which seats in the recess 19.

Considering Fig. 3 of the drawing, it will appear that the tongue 26 has a recess 27 on its inner surface registering with the recess 21 and adapted to receive the other portion of the spring 22. The tongue 26 also has a slit or recess 28 for receiving the other end 29 of the spring.

The tongues 20 and 26 have registering countersunk apertures 30 and 31 for receiving a rivet pin 32. In assembling the parts, the spring is tensioned to the position illustrated in Fig. 2, the

2

parts brought together with the ends 24 and 29 in the notches 23 and 28 and the pin 32 is placed in position and riveted over to form the assemblage as seen in Fig. 3.

5 The free end of the link 15 has an undercut rounded surface 33 which seats upon a correspondingly formed end 34 of the part 14, so that when the link 15 is in normal position, held there by tension of the spring 22, the front part of the bracket becomes continuous and the article, such as the belts, are free to be moved thereover. In this way, any one belt can be positioned to the link station 15 and by simply moving the belt or the buckle 17 thereof upwardly, the same can be 10 quickly and easily detached from the bracket.

In the same sense, articles such as belts can be 15 easily attached to the bracket by simply pressing upwardly upon the link 15 against the tension of the spring 22 and then moved onto the part 14 20 of the bracket, after which the link will automatically close and the article can then be positioned at any desired position on the bracket.

In Figs. 4 and 5 of the drawing, I have shown 25 a modified form of construction in which a suitable standard or base 35 is provided at the upper end of which are four extending arms 36, which in the construction shown, are wide spread to support a large loop frame 37. The frame 37 comprises two substantially similar U-shaped 30 parts 38 and 38' to each of which two of the arms are secured, in such manner that U-shaped hangers, such as the hanger 39 shown in Fig. 5 are free to move to any position on the frame 37, and are retained against displacement therefrom. 35 Each hanger 39 may be said to comprise a supporting ring having a swivelled pin 40 at its lower surface, which supports a spring clip 41 with which an article is adapted to be clamped. For example, a necktie may be secured in the clip 41 as initially indicated in dot and dash lines at 40 42 in Fig. 5.

Pivoted to one end of each part 38 and 38' is a 45 link 43 and 43', similar in all respects to the link 15. These links complete the formation of the loop of the frame 37 and facilitate coupling and uncoupling of the rings or hangers 39 from either end of the frame.

Devices of the type and kind shown in Fig. 4 50 may be utilized to display merchandise, such as neckties, facilitating the handling of the ties for examination, while retaining the same against displacement or shifting, and at the same time, the tie can either be detached from the supporting clip, or the ring or hanger 39 with the tie attached thereto may be removed from the frame 37. Devices of the kind shown in Figs. 4 and 5 55 can be used for mounting on a floor, counter or other support, providing a display completely around the device and articles of any type or kind can be mounted in connection therewith. In the 60

same sense, devices of the type and kind, as shown in Fig. 1, can be utilized to support articles of any type or kind where the article has a loop or opening into and through which the rod of the bracket can be passed.

The device as shown in Fig. 1, is intended primarily for the support of belts in the home, so that belts may be kept at one definite position in a closet or on a closet door, to be accessible for use at any time.

Having fully described my invention, what I claim as new and desire to secure by Letters Patent is:

1. An article supporting device of the character described comprising a frame in the form of an elongated loop, means for mounting the frame in connection with a support, with at least part of the loop spaced with respect to the support, said loop having a link portion pivotally mounted in the frame by a pivot pin the axis of which is in the plane of said loop, the link portion being normally supported in closed position completing the structure of said loop, said link being movable into raised position at right angles of the plane of the loop to provide in the loop an admission and discharge opening, tensional means normally supporting the link in closed position, and said tensional means comprising a coil spring mounted on said pivot pin and housed and concealed within and between abutting surfaces of the link and frame.

2. An article supporting device of the character described comprising a frame in the form of an elongated loop, said frame being rectangular in cross-sectional form, means for mounting the frame in connection with a support, with at least part of the loop spaced with respect to the support, said loop having a link portion pivotally mounted in the frame by a pivot pin the axis of which is in the plane of said loop, the link portion being normally supported in closed position completing the structure of said loop, said link being movable into raised position at right angles to the plane of the loop to provide in the loop an admission and discharge opening, tensional means normally supporting the link in closed position, said tensional means comprising a coil spring mounted on said pivot pin and housed and concealed within and between abutting surfaces of the link and frame, the free end of the link having an offset part adapted to seat on a corresponding cutout portion of the frame in retaining the link in closed position, and the supporting means of said frame comprising apertured plates arranged at spaced intervals on one side of the frame.

3. An article supporting device of the character described comprising a frame in the form of an elongated loop, said frame being rectangular in cross-sectional form, means for mounting the frame in connection with a support, with at least part of the loop spaced with respect to the support, said loop having a link portion pivotally mounted in the frame by a pivot pin the axis of which is in the plane of said loop, the link portion being normally supported in closed position completing the structure of said loop, said link being movable into raised position at right angles to the plane of the loop to provide in the loop an admission and discharge opening, tensional means normally supporting the link in closed position, said tensional means comprising a coil spring mounted on said pivot pin and housed and concealed

within and between abutting surfaces of the link and frame, the free end of the link having an offset part adapted to seat on a corresponding cutout portion of the frame in retaining the link in closed position, and the support of said frame comprising a standard having arms connected to opposed sides of the loop at spaced intervals.

4. An article supporting device of the character described comprising a frame in the form of an elongated loop, said frame being rectangular in cross-sectional form, means for mounting the frame in connection with a support, with at least part of the loop spaced with respect to the support, said loop having a link portion pivotally mounted in the frame by a pivot pin the axis of which is in the plane of said loop, the link portion being normally supported in closed position completing the structure of said loop, said link being movable into raised position at right angles to the plane of the loop to provide in the loop an admission and discharge opening, tensional means normally supporting the link in closed position, said tensional means comprising a coil spring mounted on said pivot pin and housed and concealed within and between abutting surfaces of the link and frame, the free end of the link having an offset part adapted to seat on a corresponding cutout portion of the frame in retaining the link in closed position, and the upper surface of the frame having grooves spaced longitudinally thereof for spacing articles supported on the frame.

5. In a device for the slidable support of articles, an elongated supporting loop member, a section of said supporting member comprising a movable link, one end of said link being pivotally coupled with a fixed portion of said member by a pivot pin the axis of which is in the plane of said loop member, the other end of said link having an undercut surface registering with another fixed portion of said member to limit the pivotal movement of said link and to provide a common alinement of said link with the fixed portions of said member, the abutting surfaces of the pivot end of said link and said member having recesses disposed coaxially of the pivot pin, and a coil spring concealed within said recesses and arranged coaxially of said pivot pin and yieldably supporting said link in alinement with the fixed portions of said member.
